ATTORNEYS

UNITED STATES PATENT OFFICE.

CHARLES S. FRENCH, OF ECKMAN, WEST VIRGINIA.

SAND DRIER.

Application filed January 10, 1923. Serial No. 611,894.

To all whom it may concern:

Be it known that I, CHARLES S. FRENCH, a citizen of the United States, and a resident of Eckman, in the county of McDowell, 5 State of West Virginia, have invented certain new and useful Improvements in Sand Driers, of which the following is a specification.

This invention relates to sand driers, and 10 has for its object the provision of a device having a positive circulation of hot air in close association with downwardly flowing sand passing through the drier.

Another object of the invention is the provision of a device in which cool air is drawn in between a corrugated fire-box lining and the outer casing of the fire-box, cooling the lining, mixing with the products of combustion from the fire-box and then the mixture 20 is conducted in close association with the sand.

A further object of the invention is the provision of a device having an open flue above the fire-box in which a mixture of 25 heated air and the products of combustion from said fire-box are caused to travel in close association with the descending sand in the drier, the said mixture being conducted from the center of the drier through a path spaced midway between the center and the periphery of the outer casing of the drier 30 and then back to the center where it is exhausted.

A still further object of the invention is 35 the provision of a device in which the direction of flow of the heated mixture of air and products of combustion which are conducted from the center of the drier upon opposite sides of the center and then back to the 40 center again, may be reversed.

With these and other objects in view, the invention consists of certain novel features of construction, as hereinafter shown and described and then specifically pointed out 45 in the claims.

In the drawings:

Figure 1 is a view in perspective of the drier in position for operation,

Figure 2 is a plan view of the same,

Figure 3 is a view in perspective of an open flue inverted for distributing hot air to the sand,

Figure 4 is a vertical section of the drier,

Figure 5 is a horizontal section taken 55 along the line 5—5 of Figure 4, and

Figure 6 is a view in perspective of the corrugated fire-box lining

Referring to the drawings, 1 designates a brick base upon which the drier is supported. Upon the base is located a grate section 2 which is in the shape of a frustum of a pyramid and having the laterally extending flanges 3 cast integrally with the section 2. A peripheral flange 4 is formed integrally with the flange 3 in upstanding relation 65 with said flange and adapted to form a means for holding the lower reduced end of the outer casing 5 of the drier.

The outer casing is in the shape of a frustum of a pyramid and inverted with its 70 larger open end at the top into which the sand is poured.

The inner walls of the grate section 2 are provided with spaced cleats 6 adjacent its corners, with the upper ends of the cleats spaced sufficiently below the upper end of the grate section in order to cause the grate 7 to extend partially into the fire-box outer casing 8. The casing 8 is likewise in the shape of a frustum of a pyramid having 80 its lower reduced end in engagement with the corners of the grate 7. The grate is provided with extensions 9 adjacent its corners adapted to rest upon the cleats 6 and thereby space the periphery of the grate from the 85 lower end of the fire-box casing 8 and the upper end of the grate section 2 in order to permit air which passes through the opening 10 in the grate section to enter between the corrugations 11 of the fire-box lining 12 90 and pass upwardly into the member 13 which has its lower end seated upon the upper end of the fire-box casing 8.

The corrugated inner lining 12 provides 95 passages between the lining and the outer casing 8 of the fire-box in order to permit air passing upwardly between the lining and the outer casing to cool the lining and prevent warping of the same.

The lining 12 is provided with an opening 14 which leads to the interior of the fire-box while the outer casing 8 of the fire box is provided with a similar opening having a flange 15 embracing the periphery of the opening except at the bottom. The top portion of the flange is V-shaped, as shown at 16, in order to direct the sand away from the top of the flanged opening and towards the perforations 17 formed in the front portion of the flange 3. The peripheral edge of 100 105 110

the flange 15 is in engagement with the inner wall of the front of the casing 5 of the sand drier. The outer casing 5 is likewise provided with an opening which is in alignment with the openings in the lining 12 and in the outer casing 8 of the fire-box. The material of the jacket or outer casing 5 at said opening is provided with inturned flanges bolted to the outer faces of the flange 15. A door is provided for said opening and is hingedly mounted on one vertical edge of said flange.

It will be noted that the casing 5 is equally spaced by reason of its frusto-pyramidal shape from the outer walls of the fire-box casing 8, and in practice I propose to space them at least two inches apart.

The member 13 is provided with an opening 19 at its upper reduced end in order to receive a section 20 of a flue. The section of the flue is substantially square-shaped and provided in its front and rear faces with triangular openings 21 and 21^a. These openings are connected to inverted V-shaped conduits 22 and 23 shown more particularly in Figure 3. An inverted V-shaped conduit 24 having open ends is provided in one face with notches 25, 26 and 27 to the peripheries of which are connected the inverted V-shaped conduits respectively 28, 22 and 29. The conduits 28 and 29 are spaced on opposite sides of the flue section 20. Parallel with the conduit 24 is a second conduit 30 which is likewise provided with three V-shaped openings 31, 32 and 33 respectively connected with the opposite ends of the conduits 28, 23 and 29.

The opposite ends of the conduits 24 and 30 are provided with flanges for connecting these ends to the opposite faces of the outer casing 5 of the drier.

A damper 34 is mounted centrally of the flue section 20 on a shaft 35 which has a vertical extension 36 extending to a point above the horizontal flues and pivotally connected to an operating handle 37. This handle extends through a perforation in the front wall of the outer casing 5. The weight of the extension 36 is sufficient to maintain the damper in any one of its predetermined positions. A pipe 38 is mounted on the flue section and extends above the upper end of the casing 5 for exhausting products of combustion from the fire-box and the heated air which passes up between the fire-box 9 and the outer casing 8 of the fire-box.

The outer casing 5 of the drier may be cast integrally or formed in four pieces with two of its sides provided with flanges which are riveted to the two other sides, shown more particularly in Figure 1.

The operation of my device is as follows: Sand is poured into the opening in the top of the casing 5 over the inverted V-shaped flues 22, 23, 24, 28, 29 and 30. The sand

travels downwardly along the sides of the outer casing 5 along the sloping sides of the sections 13 and along the outer walls of the outer casing 8 of the fire-box until it reaches the laterally extending flange 3. The sand forms a V-shaped bottom beneath the flues, 22, 23, 24, 28, 29 and 30 thereby forming a passage for free circulation of air and gases. The damper is placed in a vertical position before the fire is started in order to provide a direct passage of the gases to the atmosphere. When the fire is well under way the damper is positioned as shown in Fig. 3.

Fire is started in the fire-box with the materials for maintaining the fire being passed through the aligned openings in the fire-box lining 12, the outer casing of the fire-box and the casing 5 of the drier. The dry sand falls through the perforations 17 and 17^a which are formed in the flange 3 and then downwardly along the sloping wall of the grate section 2.

The heated air passing upwardly between the corrugated lining 12 and the outer casing 8 of the fire-box mixes with the product of combustion from the fire-box in the section 13 then passes upwardly into the flue section 20. The damper 34 being in the position shown in Figure 3 directs the mixture through the opening 21^a into the conduit 30. From this conduit the gases pass in opposite directions to the conduits 28 and 29, then into the conduit 24 through the conduit 22 and then back through the opening 21 into the flue section 20 when it is exhausted through the pipe 38 into the atmosphere.

It will be noted that the heated air passing through the conduits 22, 24, 28, 29, 30 and 23 will be in close contact with the sand passing through the drier and remove the moisture from the sand which is carried outwardly with the heated mixture from the fire-box.

When it is desired to reverse the flow of the heated mixture from that just described the crank arm 27 may be reversed in its position thereby reversing the damper 34 causing the heated mixture to pass through the opening 21 to the conduits 24, 28, 29, 30 and 23, thence through the opening 21^a into the flue section 20 then through the pipe 38 to the atmosphere. The reversal of the position of the damper 34 provides means for reversing the direction of flow of the heated gases through the inverted V-shaped flues whereby soot and other matter that has collected in the flues adjacent the exhaust ports 21 and 21^a will be burned by the heated gases from the fire-box. The oscillation of the damper in the flue section 20 scrapes off any soot which has collected therein and thereby provides a means for preventing clogging of said section.

The heated air which is carried up sep-

arately between the fire-box lining 12 and the outer casing 8 has a double function in that it not only cools the fire-box lining 12 and prevents warping of the same, but admits a quantity of air to the flues which is not required to be conducted through the fire box on its way to said flues, thereby providing for a saving of fuel. The air is heated as it passes through the corrugations and further aids in removing any moisture still in the sand when passing between the outer casing 8 of the fire-box and that portion of the casing 5 which is equally spaced at all points from the casing 8.

15 What I claim is:

1. A sand drier comprising an outer casing forming a sand hopper, a fire-box within the casing, means for conducting the heated products of combustion from the fire-box to a point adjacent the top of the casing, means for conducting said heated gases in a path from the center of the casing around the interior of the casing and spaced from the center, then back to the center and in close association with the moving sand.

2. A sand drier comprising an outer casing forming a sand hopper, a fire-box within the casing, means for conducting the heated products of combustion from the fire-box to a point adjacent the top of the casing, means for conducting said heated gases in a path from the center of the casing around the interior of the casing and spaced from the center, then back to the center and in close association with the moving sand, and means for reversing the direction of flow of the heated gases through the last-mentioned means.

3. A sand drier comprising an outer casing forming a sand hopper, a fire-box within the casing, means for conducting the heated products of combustion from the fire-box to a point adjacent the top of the casing, means for conducting said heated gases in a path from the center of the casing around the interior of the casing and spaced from the center, then back to the center and in close association with the moving sand, and means for separately conducting heated air to the last-mentioned means.

4. A sand drier comprising an outer casing forming a sand hopper, a fire-box within the casing, means for conducting the heated products of combustion from the fire-box to a point adjacent the top of the casing, means for conducting said heated gases in a path from the center of the casing around the interior of the casing and spaced from the center, then back to the center and in close association with the moving sand.

5. A sand drier comprising an outer casing forming a sand hopper, a fire box within the casing, means for conducting the heated products of combustion from the fire box to a point adjacent the top of the cas-

ing, means for conducting said heated gases in a path away from the center of the casing and around the interior of the casing, said path being spaced from the center and back to the center and in close association with the moving sand, said means for conducting the heated products of combustion from the fire box being spaced from the side walls of the fire box and in open communication with the atmosphere below the fire box for directing fresh air around the fire box through the heated products of combustion above said fire box.

6. A sand drier comprising an outer casing forming a sand hopper, a fire-box within said casing, a flue for conducting the products of combustion from the fire-box to a point adjacent the top of the casing, conduits having open bottoms arranged in open communication with each other and spaced from the sides and center of the outer casing, a centrally disposed flue connected with the fire-box and conduits connecting certain of the first-mentioned conduits with said flue whereby the hot gases of combustion from the fire-box are circulated in close association with the moving sand in the hopper.

7. A sand drier comprising an outer casing forming a sand hopper, a fire-box within said casing, a flue for conducting the products of combustion from the fire-box to a point adjacent the top of the casing, conduits having open bottoms arranged in open communication with each other and spaced from the sides and center of the outer casing, a centrally disposed flue connected with the fire-box and conduits connecting certain of the first-mentioned conduits with said flue whereby the hot gases of combustion from the fire-box are circulated in close association with the moving sand in the hopper, and means in the flue for causing the hot gases to flow from one side of the flue to the conduit to the opposite side of the flue.

8. A sand drier comprising an outer casing forming a sand hopper, a fire-box within said casing, a flue for conducting the products of combustion from the fire-box to a point adjacent the top of the casing, conduits having open bottoms arranged in open communication with each other and spaced from the sides and center of the outer casing, a centrally disposed flue connected with the fire-box and conduits connecting certain of the first-mentioned conduits with said flue, whereby the hot gases of combustion from the fire-box are circulated in close association with the moving sand in the hopper, and means in the flue for causing the hot gases to flow from one side of the flue to the conduit to the opposite side of the flue, said last-mentioned means being movable to change the direc-

tion of flow of the gases through the conduits.

9. A sand drier comprising an outer casing forming a sand hopper, a fire-box within said casing, conduits having open bottoms arranged in open communication with each other and spaced from the sides and center of the outer casing, a centrally disposed flue connected with the fire-box and 5 conduits connecting certain of the first-mentioned conduits with said flue whereby the hot gases of combustion from the fire-box are circulated in close association with the moving sand in the hopper, means in the 10 flue for causing the hot gases to flow from one side of the flue through the conduits to the opposite side of the flue, and means for diverting a portion of the air conducted towards the fire-box around the fire-box and 15 to the centrally disposed flue.

10. In a sand drier, a grate supporting section having a lateral flange projecting outwardly from its upper periphery and provided with a plurality of spaced perforations, a grate mounted in the upper end of the grate supporting section with a portion of the grate projecting above the lateral flange, a fire-box comprising an outer casing having its upper and lower end open 20 with the periphery of the lower end in engagement with the periphery of the grate, a fire-box lining inserted within the casing and having its wall corrugated with its lower end resting on the grate, whereby an 25 air space is provided between the lining and the outer casing of the fire-box, portions of the periphery of the grate being spaced from the lower end of the outer casing to provide an open communication between 30 the corrugated lining in the outer casing and the grate supporting section.

11. A sand drier comprising an outer cas-

ing forming a sand hopper, a fire-box within the casing, a flue centrally disposed on the casing and connected with the fire-box, 45 a plurality of flues in open communication with the centrally disposed flue and having a bottom portion open whereby the hot gases from the fire-box are conducted in close association with the sand, and means for causing the hot gases from the centrally disposed flue to be conducted from one side of the flue to the conduits in opposite directions back to the centrally disposed flue where said gases are exhausted. 50

12. A sand drier comprising an outer casing forming a sand hopper, a fire-box within the casing, a flue centrally disposed on the casing and connected with the fire-box, 60 a plurality of flues in open communication with the centrally disposed flue and having bottom portions open whereby the hot gases from the fire-box are conducted in close association with the sand, and means for causing the hot gases from the centrally disposed flue to be directed from one side of the flue to the conduits in opposite directions back to the centrally disposed flue where said gases are exhausted, said last 65 means including movable means for scraping soot collected in the centrally disposed flue. 70

13. A sand drier comprising an outer casing forming a sand hopper, a fire-box within the casing, a flue section connected with 75 the fire-box, horizontal flues in open communication with the flue section, a damper in the flue section pivotally mounted centrally of said section, means for oscillating the damper whereby soot collected in 80 the flue section is scraped from the wall of said section by the side edges of the damper. 85

CHARLES S. FRENCH.
